UNITED STATES PATENT OFFICE.

OTTO SCHMIDT, OF MANNHEIM, GERMANY, ASSIGNOR TO BADISCHE ANILIN & SODA FABRIK, OF LUDWIGSHAFEN-ON-THE-RHINE, GERMANY, A CORPORATION.

CHLOR-ARALKYL-SULFONIC ACIDS AND PROCESS OF MAKING SUCH COMPOUNDS.

1,025,652.

Specification of Letters Patent.

Patented May 7, 1912.

No Drawing.

Application filed March 23, 1911. Serial No. 616,448.

To all whom it may concern:

Be it known that I, OTTO SCHMIDT, Ph. D., chemist, subject of the King of Prussia, residing at Mannheim, Germany, have invented new and useful Improvements in Chlor-Aralkyl-Sulfonic Acids and Processes of Making Such Compounds, of which the following is a specification.

I have discovered that chlor-aralkyl-sulfochlorids containing chlorin in the alkyl group can be converted into the corresponding chlor-aralkyl sulfonic acids by treating them with a saponifying agent under mild conditions, that is to say, by such treatment that the sulfochlorid group is saponified to the sulfonic acid group, while the chloralkyl group remains unattacked. This can be effected, for instance, by treatment with limited quantities of water in the presence 20 of alcohol. Chlor-aralkyl-carboxylic-acid chlorids containing chlorin in the alkyl group can also be converted into the corresponding chlor-aralkyl-carboxylic acids, for instance by treatment with cold concentrated 25 sulfuric acid.

The chlor-aralkyl-sulfonic acids which can be obtained according to my invention are new and are characterized by being colorless and hygroscopic, and upon boiling with 30 water they give rise to aralkyl-alcohol-sulfonic acids, and upon treatment with dimethyl-anilin give rise to sulfonic acids of dimethyl-phenyl-aralkyl-ammonium hydroxids, in the form of an inner anhydrid thereof. 35 The chlor-aralkyl sulfochlorids which are employed in carrying out my invention and their preparation are described in the specification of the application for Letters Patent Serial No. 616,449, while the sulfonic 40 acids of dimethyl-phenyl-aralkyl-ammonium hydroxids are described and claimed in the specification of the application for Letters Patent Serial No. 584,131.

The following examples will serve to illustrate further the nature of my invention and how it can be carried into practical effect, but the invention is not confined to these examples. The parts are by weight.

Example 1: Dissolve two hundred and 50 twenty-five parts of benzyl-chlorid-para-sulfochlorid in eighty parts of alcohol, heat the solution on the water-bath and add, gradually, while stirring, eighteen parts of water. Continue heating until the evolution

of hydrochloric acid ceases and then distil 55 off the excess of alcohol at about eighty degrees centigrade, preferably *in vacuo*. The residue consists chiefly of benzyl-chlorid-para-sulfonic acid and solidifies after standing for a considerable time. It is easily 60 soluble in cold water and, on neutralization with a base in the cold, the corresponding salt can be obtained. The reaction which takes place can be represented by the following formula

In a similar manner, other chlor-aralkyl-sulfonic acids can be obtained from the corresponding chlorids, for instance 2-chlor-1-benzyl-chlorid-4-sulfochlorid gives rise to 2-chlor-1-benzyl-chlorid-4-sulfonic acid. The foregoing example can also be carried out by allowing the benzyl-chlorid-sulfochlorid 75 to stand for some time in admixture with cold alcohol, whereupon water is added and the whole is warmed; or the sulfochlorid can be directly heated with dilute alcohol. Instead of alcohol, other organic solvent can 80 be employed, such for instance as acetone, or a benzyl-chlorid-sulfonic acid itself which has the power of dissolving both benzyl-chlorid-sulfochlorid and water. If desired, however, such additions can be dispensed 85 with. If, in the foregoing example, the benzyl-chlorid-para-sulfochlorid be replaced by an equivalent quantity of benzal-chlorid-meta-sulfochlorid, the corresponding benzal-chlorid-meta-sulfonic acid is obtained. 90

Example 2: Introduce thirty parts of benzyl-chlorid-para-carboxylic-acid chlorid (obtainable by chlorinating para-toluic acid-chlorid in the presence of heat) into two hundred parts of ninety-eight per cent. sulfuric acid while maintaining a temperature of from zero to five degrees centigrade. When the evolution of hydrochloric acid ceases, pour the solution onto ice and filter off the benzyl-chlorid-para-carboxylic acid 100 and wash it with cold water. It is almost insoluble in cold water and melts at about 105 from one hundred and ninety to one hun-

dred and ninety-two degrees centigrade under decomposition. The reaction which takes place can be represented by the following formula

aralkyl-sulfonic acids which when pure are colorless and hygroscopic and which upon treatment with boiling water give rise to 25 aralkyl-alcohol-sulfonic acids and which upon treatment with dimethyl-anilin give rise to sulfonic acids of dimethyl-phenyl-aralkyl-ammonium hydroxids in the form of 30 an anhydrid thereof.

4. As a new article of manufacture benzyl-chlorid-para-sulfonic acid which when pure is colorless and hygroscopic, upon boiling with water gives rise to benzyl-alcohol-para-sulfonic acid and upon treatment with dimethyl-anilin gives rise to dimethyl-phenyl-para-sulfo-benzyl-ammonium hydroxid in the form of an anhydrid thereof.

In testimony whereof I have hereunto set 40 my hand in the presence of two subscribing witnesses.

OTTO SCHMIDT.

Witnesses:

J. ALEC. LLOYD,
S. H. SHANK.

- Now what I claim is:—
1. The process of producing omega-chloroaralkyl acids by treating omega-chloroaralkyl acid chlorides with a saponifying agent under mild conditions substantially as hereinbefore described.
  2. The production of benzyl-chlorid-para-sulfonic acid by heating benzyl-chlorid-para-sulfo-chlorid with water in the presence of alcohol.
  3. As new articles of manufacture chlor-
